UNITED STATES PATENT OFFICE

WILLIAM E. BIHL AND AXEL RAMCLAW, OF CHICAGO, ILLINOIS, ASSIGNEES TO ZERO-ZONE CORPORATION, OF CHICAGO, ILLINOIS, A CORPORATION OF ILLINOIS

DISPENSING MACHINE

Application filed January 22, 1930. Serial No. 422,511.

This invention relates to dispensing machines.

In our copending applications, Serial No. 131,634, filed August 26, 1926, and Serial No. 190,711, filed May 12, 1927, we disclose a coin controlled machine for dispensing cooled drinks and beverages such as pop and the like.

The instant invention which may be considered an improvement on the disclosure on our copending applications, relates primarily to a machine of this kind, although the invention is applicable to other types of machines of the same general class and is not therefore to be limited to machines for dispensing cooled beverages.

In the copending applications above referred to bottles of pop or other similar beverages are disposed in an upright position in a ramp which describes a path around a cooling medium disposed within a suitable housing so that the bottles are cooled to the desired temperature by the cooling medium. The deposit of a coin in the coin chute of the machine releases the mechanism so that by the operation of a crank projecting from the front of the machine, the bottles in the ramp are moved and one of them discharged through a trap door and chute leading to the exterior of the machine.

In the machines of our prior applications the bottles are moved by a pusher which is actuated by a cable or rope threaded through suitable pulleys disposed on the ramp and around a windlass, which is operated by the crank mechanism of the machine. The pusher is necessarily disposed back of the last bottle in the ramp, and to dispense a bottle from the ramp it is necessary that the pusher move all of the bottles on the ramp.

In certain instances, such as are encountered when the machine is fully loaded, the irregular path that the ramp defines makes it difficult for a pusher located behind the last bottle on the ramp to push the entire string of bottles.

For example, if the cooling tank is elliptical in shape and the ramp fitted around it, the bottles must be made to move over a generally helical path and certain of the bot-

titles are moved in an opposite direction to the movement of the other bottles. The result is that the bottles bind in the ramp and a very appreciable force must be exerted on the crank mechanism of the machine to successfully discharge a bottle from it.

In our present invention we have improved the operation of the machine by providing in addition to the pusher located behind the last bottle on the ramp, a plurality of mechanisms which engage the string of bottles at various points. When the crank mechanism of the machine is operated the pusher is moved and the auxiliary mechanisms are operated to push the bottles that they engage. In effect, instead of applying the power to move the string of bottles wholly at one point we are now applying it at several points along the string so that the tendency of the bottles to bind in the ramp is thereby reduced and the movement of the bottles made possible by the exertion of a smaller force upon the crank mechanism of the machine.

We have further improved the machine by making the cooling medium circular instead of elliptical and the ramp circular. As the bottles are moved along the ramp they bear over against the outside edge of the ramp and move in an arcuate path of uniform curvature with the result that the bottles are less liable to bind in the ramp and their movement thereby made easier.

While bottles are mentioned as being the articles to be dispensed by the machine, obviously the application of our invention is not limited to the movement of bottles, nor is it limited to a machine in which a cooling unit is employed to keep the articles dispensed at a certain temperature. Any solid objects capable of being disposed in a ramp can be moved through that ramp by the mechanism of our invention.

Now to acquaint those skilled in the art with the teachings of our invention, reference is made to the accompanying drawings in which a preferred embodiment of it is shown by way of example only, and in which

Figure 1 is a cross-sectional view of a dispensing machine equipped in accordance with the teachings of our invention;

Figure 2 is a cross-sectional view taken along the line 2—2 of Figure 1 looking in the direction of the arrows;

Figure 3 is a detailed view of the auxiliary 5 pusher of our invention; and

Figure 4 is a cross-sectional view taken along the line 4—4 of Figure 3.

The dispensing machine comprises a cabinet 10 consisting of inner wall 1 and outer wall 2 with a suitable sheet insulation 3 interposed between the two walls. As shown, this cabinet is of substantially square cross-section and of a height greater than either dimension of the section, although any preferred shape 15 and size of cabinet can be used.

Preferably the walls 1 and 2 of the cabinet are made of sheet metal and the insulation contained between them in accordance with the modern practice exercised in the construction 20 of cabinets of this kind.

The interior of the cabinet is reached by the door 4 located at the side of the cabinet and constructed in substantially the same manner as the walls of the cabinet. This 25 door is hinged and locks in the usual manner by devices not shown on the drawings.

Within the rectangular space formed by the wall 1 of the cabinet is located the cooling 30 chamber 5, the ramp 6, and the mechanism 7 for controlling the operation of the machine. Preferably the cooling chamber 5 is cylindrical in shape and the ramp 6 made to describe a helical path around this cylinder. The 35 cooling chamber 5 may be a can filled with melting ice, or preferably it is the cooling medium of a mechanical refrigerating plant, and while shown as a solid cylinder it may be either a coiled pipe or a plurality of vertical pipes, or any other arrangement of the cooling 40 medium circulating system of a mechanical refrigerating system, as long as the general shape of the arrangement is cylindrical.

As shown, the machine is designed to dispense beverages such as pop, which are contained 45 in the bottles 8, those bottles being stood upon end in the ramp, as shown in the drawings.

The ramp comprises a plurality of generally U-shaped bracket members 10 in the 50 closed bend of which is placed a supporting rail 11 upon which the bottoms of the bottles rest. Guard rails 12 and 13 are attached to the upper ends of the U brackets 10 and serve as side supports for the articles supported 55 on the rail 11. Preferably the ramp so formed winds its way from the top of the cylindrical chamber 5 down and around that chamber and terminates in a tangential portion 14 adjacent the discharge slot 15 of the 60 machine.

The details of this discharge slot are not of the essence of the present invention since any preferred arrangement capable of permitting the withdrawal of a bottle from the machine 65 and at the same time preventing excessive in-

gress of warm air into it, can be used within the teachings of our invention.

The length of the ramp may be varied in the teachings of our invention, but preferably it is sufficiently long to hold a large quantity 70 of bottles, so that the bottles which are relatively warm when they are placed in the machine will remain in the machine long enough to insure that their temperature is reduced to that of the interior of the machine 75 before they are dispensed from it. In practice we have found that a ramp capable of holding approximately 100 bottles is satisfactory even when the sale of beverages from machine is brisk and the bottles rapidly withdrawn. 80

Normally, withdrawal of the articles in the machine is prevented by the stop wheel 20 which rests against the first bottle 21 in the machine, and which is normally prevented 85 from rotating by the lever 22. This lever is connected through a control lever 23 to the control mechanism indicated generally at 24, and the lever 23 is held rigid by that mechanism until a coin is deposited in the slot 25 90 and the mechanism operated thereby to release a bottle from the machine.

The control mechanism also comprises a windlass drum 26 around which is wound the driving cable 27, that cable being threaded 95 through idler pulleys 28 and driving pulleys 29, both of which are located on the ramp 6. At the top of the ramp, the cable 27 leaves the last pulley 28 on the ramp and is threaded around idler pulley 30 attached to the body 100 of the cabinet near its top. From the pulley 30 the cable 27 runs down outside of the ramp to a second idler pulley 31 and from there back to the windlass 26.

A pusher 32 is disposed on the ramp 105 behind the last one 33 of the bottles 8, and bears against that bottle to push it and the one ahead of it through the ramp. The pusher 32 comprises a main body to which the cable 27 is attached at 34, and the wheels 35 and 36 which bear against the inside lower rail 13 of the ramp. By this arrangement a movement of the cable 27 responsive to a turning of the windlass drum 26 moves the pusher 32 in the ramp and slides the bottles 110 33 and 8 along in the ramp toward the discharge chute 15.

Inasmuch as the ramp 6 makes a plurality of convolutions around the cooling unit 5 in a substantially helical path, the amount of force required to be placed on the last bottle 33 by the pusher 32 to move the entire string of approximately 100 bottles is more than can be conveniently applied by the windlass 120 26. This is because of the tendency of the bottles to buckle and get out of line with a consequent increase in the friction between the bottles and the side rails of the ramp. 125

To eliminate this trouble and to further the movement of the bottles in the ramp by 130

the windlass 26 we have provided a plurality of star wheels shown in detail in Figures 3 and 4, which star wheels comprise the stars 40 mounted upon a vertical shaft 41 which is disposed along the outside edge of the ramp.

Along the inside edge of the ramp 6 and supported on the same U-shaped bracket 10 as the star wheel is a driving pulley 29 around which the driving cable 27 is threaded as hereinbefore pointed out.

The driving pulley 29 is mounted upon a shaft 42 which projects through the bottom member 43 of the U-shaped bracket 10, and is so located that the pulley 29 rests on top of the member 43 and in the pocket-like part 44 of the bracket 10. The upper surface of the pulley is disposed below the upper surface of the supporting rail 11 so that the presence of the pulley in the ramp does not in any way interfere with the movement of bottles through the ramp.

On the lower end of the shaft 42 and below the bracket member 43 is a driving gear 45 which is rigidly attached to the shaft 42 and rotated by it. A smaller driving gear 46 is pivoted to the member 43 on the underside of it and meshes with the gear 45, the gear 46 in turn meshing with a similar gear 47 also located beneath the bracket member 43. The gear 47 meshes with a fourth gear 48 attached to the lower end of the shaft 41. Through the operation of this gear train, a movement of the driving pulley 29 is transmitted to the shaft 41, and that shaft is rotated thereby.

The star wheel 40 is not rigidly attached to the shaft 41 but rather is provided with a ratchet wheel 49 with the teeth of which the pawl 50 is engaged. The pawl 50 is carried upon the gear 48 so that a movement of that gear in counter-clockwise direction, Figure 3, causes the pawl 50 to engage the tooth of the ratchet wheel 49 and to drive the star 40 in a counter-clockwise direction.

In one embodiment of our invention we have located the star wheel 40 and the companion drive gears therefor at a plurality of points on the ramp 6 so that the teeth of the star wheels engage every twelfth bottle on the ramp. By this arrangement instead of applying the driving power solely to the back bottle of the group by the pusher 32, we applied this driving power to a plurality of points along the string of bottles.

Since there are but twelve bottles intervening between the points of application of the driving power, that driving power can push those twelve bottles without encountering undue side friction caused by the buckling of the string of bottles. The movement of the entire string of bottles through the ramp is therefore facilitated by the auxiliary pushing of the star wheels, and the windlass 26 can

easily be operated to dispense a bottle from the machine.

Obviously the particular spacing of the star wheels around the ramp 6 can be varied to meet the desired requirements of ease of operation. While we have employed a star wheel for every twelve bottles in the one embodiment of our invention, we are not to be limited to this as more or fewer bottles can be included between adjacent star wheels.

As was brought out in our above mentioned copending applications, the machine is re-loaded by operating the windlass 26 in the opposite direction to move the pusher 32 back to its starting point, that is, at the end of the ramp farthest away from the discharge chute 15 of the machine. For this operation, the windlass 26 is turned by the handle 51 and the cable 27 moved in the opposite direction than that taken by it when the bottle is being dispensed from the machine.

This reverse movement of the cable 27 drives the driving pulley 29 in the opposite directions and through the gear wheels 46 and 47, the gear 48 is driven in a clockwise direction, Figure 3.

With the gear 48 moving in a clockwise direction the pawl 50 rides over the teeth of the ratchet wheel 49 without moving that wheel. By this arrangement, the pusher 32 can be moved to its starting point without moving the bottles which are in the ramp at the time and engaged by the star wheels 40. Additional bottles are added to the ramp ahead of the pusher 32, and when the last bottle has been added the pusher is again moved into engagement with the last bottle 33 of the group.

The star wheel 20 which engages the first bottle 21 of the bottles in the ramp, and which is normally locked by the lever 22 and unlocked at the start of the movement of the windlass 26, is again locked immediately after the bottle 21 has been discharged into the chute 15 through the operation of the link 52 which engages this last bottle 21 and exercises a control over the driving mechanism of the windlass 26 through the lever 53. However, the details of this driving mechanism and its control by the link 52 and lever 53 are not of the essence of the present invention and are shown in full in our copending application, Serial No. 422,513 filed Jan. 22, 1930 to which application reference is here made for those details.

While we have disclosed our invention by illustrating a preferred embodiment of it, we have done so by way of example only as there are many modifications and adaptations which can be made by one skilled in the art within the scope and teachings of our invention.

Having thus complied with the statutes and shown and described a preferred embodiment of our invention, what we consider new and

desire to have protected by Letters Patent is pointed out in the appended claims.

What is claimed is:

1. In a bottle dispensing machine, a track-way for holding a plurality of bottles in an upright position, a pusher fitted on said trackway and engaging one of said bottles, means for moving said pusher over the track-way to thereby move said bottles thereover, and means on said trackway rotated about stationary axes by said moving means to move said bottles independently of said pusher. 75
2. In a bottle dispensing machine, a track-way for holding a plurality of bottles in an upright position, a pusher fitted on said trackway and engaging one of said bottles, a plurality of pulleys attached to said trackway, a flexible cable threaded through said pulleys and attached to said pusher to move it over the trackway to thereby move said bottles thereover, and means on said trackway rotated about fixed axes by said cable and cooperating with said pusher to move said bottles. 80
3. In a bottle dispensing machine, a track-way for holding a plurality of bottles in an upright position, a pusher fitted on said trackway and engaging one of said bottles, means for moving said pusher over the track-way to thereby move said bottles thereover, and a star wheel rotated by said moving means to assist said pusher in moving said bottles. 85
4. In a bottle dispensing machine, a track-way for holding a plurality of bottles in an upright position, a pusher fitted on said trackway and engaging one of said bottles, means for moving said pusher over the track-way to thereby move said bottles thereover, and a plurality of star wheels rotated by said moving means to assist said pusher in moving said bottles. 90
5. In a bottle dispensing machine, a track-way for holding a plurality of bottles in an upright position, a pusher fitted on said trackway and engaging one of said bottles, a plurality of pulleys attached to said trackway, a flexible cable threaded through said pulleys and attached to said pusher to move it over the trackway to thereby move said bottles thereover, and a star wheel rotated by said cable to assist said pusher in moving said bottles. 95
6. In a bottle dispensing machine, a track-way for holding a plurality of bottles in an upright position, a pusher fitted on said trackway and engaging one of said bottles, a plurality of pulleys attached to said track-way, a flexible cable threaded through said pulleys and attached to said pusher to move it over the trackway to thereby move said bottles thereover, and a plurality of star wheels rotated by said cable to assist said pusher in moving said bottles. 100
7. In a bottle dispensing machine, a track-way for holding a plurality of bottles in an upright position, a pusher fitted on said trackway and engaging one of said bottles, means for moving said pusher over the track-way to thereby move said bottles thereover, and means on said trackway rotated about fixed axes by said moving means and cooperating with said pusher to slide said bottles along said trackway. 105
8. In a dispensing machine, a ramp which describes a substantially helical path and is arranged to hold a plurality of the articles to be dispensed by the machine, a pusher disposed on said ramp behind said articles, means for moving said pusher to move said articles along said ramp, and an auxiliary pusher operated by said means and having means for engaging said articles to assist in pushing them along said ramp. 110
9. In a dispensing machine, a ramp which describes a substantially helical path and is arranged to hold a plurality of the articles to be dispensed by the machine, a pusher disposed on said ramp behind said articles, means for moving said pusher to move said articles along said ramp, and a plurality of auxiliary pushers operated by said means and having means for engaging said articles to assist in pushing them along said ramp. 115
10. In a dispensing machine, a ramp which describes a substantially helical path and is arranged to hold a plurality of the articles to be dispensed by the machine, a pusher disposed on said ramp behind said articles, means for moving said pusher to move said articles along said ramp, and a plurality of auxiliary pushers mounted on the outside edge of said ramp, operated by said means and having means for engaging said articles to assist in pushing them along said ramp. 120
11. In a dispensing machine, a ramp which describes a substantially helical path and is arranged to hold a plurality of the articles to be dispensed by the machine, a pusher disposed on said ramp behind said articles, a plurality of pulley wheels mounted along the inside edge of said ramp, a cable threaded through said pulleys and attached to said pusher, means for moving said cable to thereby move said pusher along said ramp to push said articles therealong, and an auxiliary pusher mounted on the outside edge of said ramp and geared to one of said pulleys and operated by it when said cable is moved and means on said auxiliary pusher for engaging said articles to assist said pusher in moving them along said ramp. 125
12. In a dispensing machine, a ramp which describes a substantially helical path and is arranged to hold a plurality of the articles to be dispensed by the machine, a pusher disposed on said ramp behind said articles, a plurality of pulley wheels mounted along the 130

inside edge of said ramp, a cable threaded through said pulleys and attached to said pusher, means for moving said cable to thereby move said pusher along said ramp to push said articles therealong, a plurality of auxiliary pushers mounted on the outside edge of said ramp, each being geared to one of said pulleys and operated by it when said cable is moved, and means on said auxiliary pushers for engaging said articles to assist said pusher in moving them along said ramp.

13. In a dispensing machine, a ramp which describes a substantially helical path and is arranged to hold a plurality of the articles to be disposed by the machine, a pusher disposed on said ramp behind said articles, a plurality of pulley wheels mounted along the inside edge of said ramp, a cable threaded through said pulleys and attached to said pusher, means for moving said cable to thereby move said pusher along said ramp to push said articles therealong, a plurality of auxiliary pushers mounted on the outside edge of said ramp, each being geared to one of said pulleys and operated by it when said cable is moved, and a star wheel on each of said auxiliary pushers for engaging said articles to assist said pusher in moving them along said ramp.

14. In a dispensing machine, a ramp comprising a U-shaped bracket, a supporting rail mounted in the closed end of said bracket and extending upward parallel to the side members of the bracket, side rails attached to said side members and extending parallel to said supporting rail, a pulley mounted above the closed end of said bracket but below and to one side of said supporting rail, a shaft for said pulley extending through said bracket, a gear mounted on said shaft below said bracket, a star wheel mounted on the opposite side of said supporting rail and above it, a shaft for said star wheel extending below said bracket, a gear on said shaft, a ratchet connection between said star wheel and said star wheel shaft gear, and a cable engaging said pulley to rotate it and said star wheel.

15. In a dispensing machine, a ramp comprising a U-shaped bracket, a supporting rail mounted in the closed end of said bracket and extending upward parallel to the side members of the bracket, side rails attached to said side members and extending parallel to said supporting rail, a pulley mounted above the closed end of said bracket but below and to one side of said supporting rail, a shaft for said pulley extending through said bracket, a gear mounted on said shaft below said bracket, a star wheel mounted on the opposite side of said supporting rail and above it, a shaft for said star wheel extending below said bracket, a gear on said shaft, a ratchet connection between said star wheel and said star wheel shaft gear, and a cable engaging said pulley to rotate it and said star wheel.

16. In a dispensing machine, a ramp comprising a U-shaped bracket, a supporting rail mounted in the closed end of said bracket and extending upward parallel to the side members of the bracket, side rails attached to said side members and extending parallel to said supporting rail, a pulley mounted above the closed end of said bracket but below and to one side of said supporting rail, a shaft for said pulley extending through said bracket, a gear mounted on said shaft below said bracket, a star wheel mounted on the opposite side of said supporting rail and above it, a shaft for said star wheel extending below said bracket, a gear on said shaft, a ratchet connection between said star wheel and said star wheel shaft gear, and a cable engaging said pulley to rotate it and said star wheel.

17. In a dispensing machine, a ramp comprising a U-shaped bracket, a supporting rail mounted in the closed end of said bracket and extending upward parallel to the side members of the bracket, side rails attached to said side members and extending parallel to said supporting rail, a pulley mounted above the closed end of said bracket but below and to one side of said supporting rail, a shaft for said pulley extending through said bracket, a gear mounted on said shaft below said bracket, a star wheel mounted on the opposite side of said supporting rail and above it, a shaft for said star wheel extending below said bracket, a gear on said shaft, a ratchet connection between said star wheel and said star wheel shaft gear, and a cable engaging said pulley to rotate it and said star wheel.

18. In a dispensing machine, a cylindrical cooling element, a ramp describing a helical path around said element, said ramp being adapted to hold a plurality of articles to be dispensed by the machine, and means engaging a plurality of ones of said articles for pushing them along said ramp to dispense them from said machine.

19. In a dispensing machine, a cylindrical cooling element, a ramp describing a helical path around said element, said ramp being adapted to hold a plurality of articles to be dispensed by the machine, and means including a pusher behind said articles and a star wheel engaging one of them for pushing them along said ramp to dispense them from said machine.

20. In a dispensing machine, a cylindrical cooling element, a ramp describing a helical path around said element, said ramp being adapted to hold a plurality of articles to be dispensed by the machine, and means engaging a plurality of ones of said articles for

wheel shaft gear to said pulley shaft gear.

16. In a dispensing machine, a ramp comprising a U-shaped bracket, a supporting rail mounted in the closed end of said bracket and extending upward parallel to the side members of the bracket, side rails attached to said side members and extending parallel to said supporting rail, a pulley mounted above the closed end of said bracket but below and to one side of said supporting rail, a shaft for said pulley extending through said bracket, a gear mounted on said shaft below said bracket, a star wheel mounted on the opposite side of said supporting rail and above it, a shaft for said star wheel extending below said bracket, a gear on said shaft, a ratchet connection between said star wheel and said star wheel shaft gear, and a cable engaging said pulley to rotate it and said star wheel.

17. In a dispensing machine, a ramp comprising a U-shaped bracket, a supporting rail mounted in the closed end of said bracket and extending upward parallel to the side members of the bracket, side rails attached to said side members and extending parallel to said supporting rail, a pulley mounted above the closed end of said bracket but below and to one side of said supporting rail, a shaft for said pulley extending through said bracket, a gear mounted on said shaft below said bracket, a star wheel mounted on the opposite side of said supporting rail and above it, a shaft for said star wheel extending below said bracket, a gear on said shaft, a ratchet connection between said star wheel and said star wheel shaft gear, and a cable engaging said pulley to rotate it and said star wheel.

18. In a dispensing machine, a cylindrical cooling element, a ramp describing a helical path around said element, said ramp being adapted to hold a plurality of articles to be dispensed by the machine, and means engaging a plurality of ones of said articles for pushing them along said ramp to dispense them from said machine.

19. In a dispensing machine, a cylindrical cooling element, a ramp describing a helical path around said element, said ramp being adapted to hold a plurality of articles to be dispensed by the machine, and means including a pusher behind said articles and a star wheel engaging one of them for pushing them along said ramp to dispense them from said machine.

20. In a dispensing machine, a cylindrical cooling element, a ramp describing a helical path around said element, said ramp being adapted to hold a plurality of articles to be dispensed by the machine, and means engaging a plurality of ones of said articles for

pushing them downward in said ramp to dispense them from said machine.

21. In a dispensing machine, a cylindrical cooling element, a ramp describing a helical path around said element, said ramp being adapted to hold a plurality of articles to be dispensed by the machine, and means including a pusher behind said articles and a star wheel engaging one of them for pushing them down said ramp to dispense them from said machine.

22. In a dispensing machine, a cylindrical cooling element, a ramp describing a helical path around said element, said ramp being adapted to hold a plurality of articles to be dispensed by the machine, and means including a pusher behind said articles and a star wheel engaging one of them and moved simultaneously with said pusher to push said articles down said ramp to dispense them from said machine.

23. In a dispensing machine, a cylindrical cooling element, a ramp describing a helical path around said element, said ramp being adapted to hold a plurality of articles to be dispensed by the machine, and means including a pusher behind said articles and a plurality of star wheels each engaging one of the articles and moved synchronously with the other wheels and simultaneously with said pusher to push said articles down said ramp to dispense them from said machine.

In witness whereof, we hereunto subscribe our names this 17th day of January, 1930.
